[57] CLAIM

We claim the ornamental design for a curvilinear molded plastic binder, as shown and described in FIGS. 1 to 4.

DESCRIPTION

FIG. 1 is a perspective view of our design; FIG. 2 is a left side view of our design; FIG. 3 is a top view of our design with the bottom view being the mirror image of the top view; and, FIG. 4 is a front view of our design.

The ring binding structure and the back cover depicted by means of broken lines in FIGS. 1 and 3 have been shown for illustrative purposes only and form no part of the claimed design.
